UNITED STATES PATENT OFFICE.

JOHN R. ROBERTSON, OF SELMA, ALABAMA.

GRATE.

SPECIFICATION forming part of Letters Patent No. 290,476, dated December 18, 1883.

Application filed April 28, 1883. (No model.)

To all whom it may concern:

Be it known that I, JOHN R. ROBERTSON, of Selma, in the county of Dallas and State of Alabama, have invented certain new and useful Improvements in Grates; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of a fire-place provided with my improved grate. Fig. 15 2 is a side view of the grate removed from the fire-place. Fig. 3 is a vertical section of the grate. Figs. 4 and 5 are perspective detail views of the adjustable wings, and Fig. 6 is a longitudinal vertical section of the grate.

20 Similar letters of reference indicate corresponding parts in all the figures.

My invention has relation to grates for open fire-places; and it consists in the improved construction and combination of parts of a 25 grate in which the fire-space may be adjusted to any size desired by means of two removable and adjustable side pieces, and which is provided with an ash-receptacle, thus combining the advantages of a stove and an open 30 grate into one, as hereinafter more fully described and claimed.

In the accompanying drawings, the letter A indicates the front grate, and B the bottom grate, of a basket-grate having two uprights, 35 C, supporting the front grate, and two uprights, D, supporting the rear end of the bottom grate, the said uprights standing, one pair C D at each side of the grate, connected at their upper ends by means of two cross-40 pieces, E. The rear uprights, D, are connected by and support a plate, F, forming a fire-back, which is provided upon the inner surface with two or more brackets, G, which keep the same at a distance from the back of the 45 fire-place, forming an air-space between the same and the fire-back, through which air may pass and become heated, and pass out into the room through suitable openings in the front wall of the fire-place, the brackets at 50 the same time supporting the fire-back. A perforated plate, H, having its lower por-

tion forming a hinged flap or door, I, covers the space at the front of the fire-place, between the bottom or floor of the same and the bottom grate, and is fastened to two upright plates or side pieces, J, having rearwardly-extending wings, or slides K a short distance below the bottom grate, in which the ends of a supplementary grate, L, rest and slide. In the space below this grate is placed a drawer 6c or ash-receptacle, M, to which access may be had, and which may be slid in or out through the opening covered by the hinged door I.

N N are two inclined wings or plates, which are of the same width as the depth of the grate, 65 and are provided with flanges O at their lower ends, with which they rest upon the bottom grate-bars, and with horizontally-extending plates P upon their upper ends, upon which slide two plates, Q, resting with their outer 70 ends upon the cross-pieces E. These plates or extensions are provided upon their outer edges with two arms, R, which extend inward under plates P, sliding inside two downward-bent flanges, S, upon the sides of the said 75 plates, thus enabling the extensions to be slid in or out as the wings are moved farther apart or closer together, the outer ends of the extensions always resting on the cross-pieces E. It will be seen that in this manner 80 the fire-space in the grate may be made smaller or larger, as desired, and that the perforated front plate, H, will allow the draft to pass up through the bottom of the grate, while the ashes and cinders will drop through the grate 85 and the supplementary grate into the ash receptacle or drawer.

In Fig. 5 is shown a slight modification of the adjustable extensions upon the wings, which consists in slotting plates Q longitudinally, as shown at T, through which slots pass turn-buttons U, the slots sliding up on the shanks of the turn-buttons, and the latter allowing the plates or extensions to be removed when desired. In this manner any basket-grate of the usual construction may be changed to combine all the advantages of a stove, as far as regards saving in fuel and cleanliness in collecting the cinders and ashes, with the pleasant appearance and superior ventilating 95 qualities of an open fire-place, by adding the features herein described to the same.

Having thus described my invention, I claim and desire to secure by Letters Patent of the United States—

1. The inclined wings or plates N, having 5 horizontally-extending plates P upon their upper edges, and flanges O upon their lower edges, and adapted to be placed in a basket-grate, resting with their lower flanged ends upon the bottom of the grate, and with the 10 edges of the upper plates upon the sides of the grate, as and for the purpose shown and set forth.
2. The wings or plates N, having horizontally-extending plates P upon their upper 15 edges, provided with downward-bent flanges S upon their sides and flanges O upon their lower edges, in combination with the sliding extensions Q, having inward-bent arms R extending inward under plates P from the 20 outer edges of the extensions, said wings and extensions adapted to be placed in a basket-grate, resting with their lower ends upon the bottom of the grate, and with the ends of the 25 adjustable extensions upon the sides of the grate, as and for the purpose shown and set forth.

3. The combination of the perforated front plate, H, having hinged door I at its lower edge, and side pieces, J, forming ways or slides K, supplementary grate L, and ash-drawer M, all adapted to be placed under a basket-grate in the space between the bottom of the same and the floor, as and for the purpose shown and set forth. 30

4. As an improvement in fire-grates, the 35 arrangement, as described, of the basket-grate A B, having uprights C D and fire-back F, inclined plates N, having top plates, P, and adjustable extensions Q, perforated front plate, H, hinged door I, side pieces, J, forming ways K, supplementary grate L, and ash-drawer M, all constructed and combined as and for the purpose shown and set forth. 40

In testimony that I claim the foregoing as my own I have hereunto affixed my signature 45 in presence of two witnesses.

JOHN R. ROBERTSON.
